UNITED STATES PATENT OFFICE

2,096,130

FIGURE DEVICE

Barnet Phillips, Rye, N. Y.

Application June 6, 1935, Serial No. 25,319

5 Claims. (Cl. 46—157)

The present invention is means for the production of figures from a foldable blank.

The invention aims primarily to provide means whereby a single blank or sheet of paper, cardboard, stiffened cloth or other material, printed, stamped, painted or embossed properly, may be folded and otherwise shaped so as to produce a predetermined figure which will truly represent in relief the character which it is intended to 10 simulate or portray.

Particularly, the invention pertains to a foldable device for amusement or instruction of the general character disclosed by the United States Patent to Vine No. 502,896, dated August 8, 15 1893, but which improves the idea therein expressed in such way that more complete and perfect characterization may be accomplished by the formation of additional planes, surfaces and projections (the Vine patent has only four planes) which permits of a greater variety of figures, such as the heads of birds, beasts, reptiles and fish; flower forms; and the heads of women or men or caricatures thereof.

The invention is carried out by means of the 20 structure hereinafter more fully detailed, reference being had to the accompanying drawings wherein:

Figure 1 is the face or front view of a blank from which the head of a bird is reproduced,

Figure 2 is a view of the back or reverse side of the blank after the first folds have been made,

Figure 3 is a similar view after the second folds have been made,

Figure 4 discloses the reverse side of the blank when folded as shown in the preceding figure,

Figure 5 is a side elevation showing the profile of the figure after the folding has been completed and the parts manipulated to produce the finished figure,

Figure 6 is a front elevation of the figure,

Figure 7 is a rear elevation of the bird figure.

Figure 8 is a face or front view of a blank from which may be folded or formed the head of a jester or other fantastic representation of the 45 human head,

Figure 9 is a view of the reverse side of the blank after the first folds have been made,

Figure 10 is a similar view showing the appearance after the second folds have been made,

Figure 11 is a view of the reversible side after all the primary folds have been made.

Figure 12 is a front view of the figure when completed,

Figure 13 is a side elevation or profile view of 55 the completed figure,

Figure 14 is a rear elevation of the complete figure.

Figures 1 to 7, inclusive, disclose a blank and the several cutting, folding and bending operations necessary in the production of the head of a bird. In order to accurately reproduce the desired figure, as well as to maintain the same in form, the blank is provided with certain cuts, slits and interfitting parts, and, while portions of the blank may be entirely removed, in none of the 10 many figures or caricatures which I am able to construct by my method is it necessary that material or parts be added to the blank as originally prepared.

In carrying out the invention, use is made of a blank of paper, linen, cardboard, or other foldable material capable of having printed or painted thereon embellishments or parts of the figure it is desired to reproduce as a composite. The blank is preferably of rectangular form of equal length 15 and breadth, and is provided with major or primary lines of folds A, B, C, D, E, F, and G. The lines A are spaced equi-distantly and parallel the top and bottom edges of the blank, and the lines B are disposed at right angles thereto and parallel the sides of the blank while the major lines of fold C extend diagonally from corner to corner of the blank. The lines D, E, F and G extend across corners of the blank and intersect the central lines of the A and B groups at the edges 20 of the blank, thus describing a central square flanked by triangles lying in the corners of the blank.

The triangles in the upper opposite corners of the blank have imprinted thereon the representations of eyes 15 and head portions of the bird, and minor lines of fold 16, disposed at angles to both major fold lines, extend predetermined distances from the rectangles in the corners of the blank toward the center thereof. Incisions are made 25 at 18 and 19 as well as upon a curved line 20 near each upper corner of the blank in order that sections of the bird's upper bill or beak may be brought into relief.

Near the opposite lower corners of the blank 30 are incisions 21 and 22, as well as minor lines of fold 23—24—25, the portions thus described constituting lower beak or bill portions of the bird. It will be observed that the portions to represent the upper and lower beak or bill portions 35 converge toward the center of the blank.

To facilitate proper folding of the blank and to prevent a pucker or undesirable thickness occurring, a diamond shaped portion of approximately the dimensions indicated at 26 is removed, while 40 45 50 55

incisions defining locking tongues 27 near the lower left hand corners of the blank constitute means for maintaining the figure in assembled position. These tongues are adapted to engage 5 within slots 28 located near the upper corners of the blank. Darts or incisions 29 in the lower corners and at the bottom and top serve to enable parts of the completed figure to be extended outwardly from the plane of the blank.

10 The inner portions of the upper bill sections of the blank are adapted for folding or bending upon the curved line 30, the corresponding bent portions 30' of the adjacent bill sections engaging each other in the completed figure. Likewise, the 15 edges of the lower bill defined by the lines 21 are to be folded upon lines 23 to provide abutting surfaces 23' in the completion of the lower bill. These portions 30' and 23' of the upper and lower bills may be glued together if desired in order 20 to hold the parts assembled.

With the blank thus imprinted and prepared for folding, the first folds are made backwardly upon major lines D, E, F and G, whereupon the blank is reversed and inverted preferably presenting the appearance as in Figure 2. Thus folded, the upper beak portions 31 and the lower beak portions 32 project radially from the body of the blank due to the incisions defining portions of said beaks. The blank is next folded 30 backwardly along upper and lower lines A as well as the outer lines B, producing the representation shown in Figure 3. At the same time, the beak portions are bent along lines 16, 30, 23 and 24. The blank is then reversed and presents the 35 configuration shown in Figure 4. When so positioned the blank is ready for the final movements to produce the composite head. With the blank in the position as shown in Figure 4, the center is depressed, causing the upper and lower beak 40 portions to move together, while the rear portion of the blank forms itself into webs or ribs represented at 33 and 34 in Figures 5 and 7. The tongues 27 during this folding movement are caused to enter and lock within their respective 45 slots 28, while the inturned portions of the upper and lower bill pieces coincide with each other. The application of glue, paste or other adhesive to these portions will firmly maintain the figure in assembled relation. Portions of the edge of 50 the blank may be bent or curved forwardly or rearwardly as desired to lend a more realistic or fantastic appearance to the composite figure.

It will thus be seen that due to the particular arrangement of major and minor lines of fold, 55 as well as the cutting of the blank described, a composite figure may be produced very closely simulating the figure intended in both front and side views. Moreover, the tongue and slot arrangement at the sides of the bill of the figure 60 permits relative movement between the upper and lower bill portions, and it will be understood that by inserting the fingers in the cells between the webs 33 and 34 life-like movements of the bill may be simulated. The webs 33 and 34 may be 65 used in handling the figure and also may be used as a support when it is desired to display the completed figure.

Figures 8 to 14, inclusive, disclose a blank so imprinted as to produce a clown or jester. In 70 this form the same major lines of fold are employed, but different minor fold lines and incisions are necessary due to the difference in appearance and profile of the figure to be composed. Opposite corners of the blank 35 and 36 75 are imprinted with eyes, face and hair repre-

sentations as shown, while a third corner 37 is imprinted to represent the lower lips and chin portion. Parts of the blank immediately adjacent to the facial representations are cut away as at 38 in order that nose and upper and lower 5 lip portions may be formed thereon in the folding process. Tongues 39 are provided adjacent to the lower jaw portions for interlocking engagement with slots 40 in upper jaw portions, while parts 40' of the blank are removed at the juncture 10 of certain lines of fold to permit of folding without puckering and to reduce thickness.

The figure here in contemplation carries a peculiar head-dress, and in order that this may be properly reproduced an incision 41 is made upon 15 one of the diagonal lines of fold C inward from the upper edges a predetermined distance. Similarly, curved slots 42 extend inwardly predetermined distances from the top and one side of the blank to permit of the head-dress being properly shaped and also to permit of the zones indicated at 43 being turned inwardly and obscured from view and to permit the bridge portions of the nose to meet. Minor lines of fold or bend 44 are provided in the head-dress portion to permit the head-dress to obtain the desired shape. The chin piece indicated at 37 is slit inwardly from one corner as at 45 to produce a flaring collar effect while the minor line of fold 46 defines the juncture of the chin with the throat. 20

It will be observed that the same inventive idea as described in the first figure is here carried forth, the only variation being minor changes in 25 incisions, tongues and slots, minor lines of fold and the pictorial representations upon parts of the blank. While in this figure all the major lines of fold are used, parts of some of them may be left unfolded in the production of the desired composite figure. Due to the variation in the 30 fold of this figure, it will be observed by reference to Figures 13 and 14 that the webs or ribs at the rear of the head assume different positions. While the webs of the bird's head produce a four cell rear structure, those of the jester provide a three-cell arrangement. It will be understood, 35 of course, that to enable the head to retain its proper folded position, glue may be applied to the mating surfaces of the face structure, whereby a rigid and permanent form is assured.

The foregoing is a description of but two forms 40 capable of being carried out under the same inventive idea, but it will be understood that a great variety of figures and shapes may equally as effectively be reproduced with only slight 45 changes in the lines of minor fold, the location and shape of incisions or parts to be removed and with variations in pictorial representation of figure parts. I wish it understood, therefore, that the invention is not necessarily to be limited 50 to those forms herein shown and described, as a great variety of shapes may be practiced in accordance with the invention as defined by the claims, some thirty different forms having already 55 been made by me.

What I claim is:

1. A blank having major lines of fold disposed at angles to each other, minor lines of fold on 60 said blank of relatively short length, pictorial representations of parts of a figure on portions of said blank, parts of said blank adjacent to certain parts of said representations adapted to be cut and projected from the plane of said blank when the latter is folded on said lines, said projected parts lying adjacent to both major and minor 65 lines of fold and constituting projecting features 70

75

of said figure when the blank has been folded properly on certain of said major and minor lines.

2. A blank having major lines of fold disposed thereon in spaced relation and at angles to each other, said lines extending to the edges of said blank, pictorial representations of parts of a figure on portions of said blank to be brought together in a composite figure when the blank is folded on proper lines, tongues integral with said blank adjacent to certain of said figure parts, said tongues adapted to be projected out of the plane of said blank, said blank having parts to cooperate with said tongues in maintaining the blank in set up position, certain of the lines of fold forming trusses at angles to each other in the rear of said figure to reinforce the same.
3. A blank provided with lines of fold and having thereon pictorial representations of parts of an animate figure, portions of said blank having 20 cuts therein to permit of the blank areas adjacent thereto to be projected from the plane of the blank, the said cut portions having pictorial representations thereon of other parts of the said animate figure, said blank when folded upon proper lines and when said cut portions are projected bringing said pictorial representations of

the cut and uncut portions of the blank into such relationships as to produce a composite animate figure.

4. A blank provided with lines of fold and having thereon pictorial representations of parts of an animate figure, portions of said blank being cut upon lines defining certain complementary parts of said pictorial representations to permit such parts to be projected out of the plane of said blank, and such parts when properly folded and 10 projected combining with other parts to form composite portions of said animate figure in relief.

5. A blank provided with a plurality of lines of fold, pictorial representations of an animate 15 figure on said blank, portions of said blank being cut upon lines defining certain complementary parts of said figure, said cut portions disposed in such relation to their respective lines of fold as to project out of the plane of the sheet 20 when folded on such lines, and said cut portions cooperating with each other and with the uncut portions of said blank to form a composite animate figure when the blank and portions are properly folded.
